UNITED STATES PATENT OFFICE.

FLOYD L. SWANBERG, OF CINCINNATI, OHIO, ASSIGNOR TO THE D. T. WILLIAMS VALVE COMPANY, OF CINCINNATI, OHIO, A CORPORATION OF OHIO.

SIGHT-FEED LUBRICATOR.

964,583.

Specification of Letters Patent. Patented July 19, 1910.

Application filed March 7, 1908. Serial No. 419,731.

To all whom it may concern:

Be it known that I, FLOYD L. SWANBERG, a citizen of the United States, residing in Cincinnati, county of Hamilton, and State 5 of Ohio, have invented certain new and useful Improvements in Sight-Feed Lubricators, of which the following is a full, clear, and exact description, reference being had to the accompanying drawings, forming 10 part of this specification.

My invention relates to what is known as sight feed lubricators, in which the oil for lubrication is contained in a suitable reservoir, and is fed by gravity in regulated 15 quantities through a sight feed chamber to the parts to be lubricated.

The invention consists in that certain novel construction and arrangement of parts to be hereinafter particularly pointed 20 out and claimed.

In the drawings Figure 1 is a central vertical section partly in elevation of my improved lubricator, with the feed valve closed. Fig. 2 is a similar vertical section 25 with the feed valve open.

The reservoir for the reception of the oil, consists of the cylindrical glass casing 1, with flanged base plate 2, and top cover 3, between which plate and cover the cylinder 30 is held, washers 4—4 being provided for a tight joint.

5 is an opening drilled in top cover 3, and closed by the sliding plate 6, and through this opening the oil is filled into the reservoir. 35

The base plate and cover for the glass cylinder are identical in construction, except for the oil supply opening, which is drilled after the plates are constructed. It results from 40 this that a large number of flanged plates can be cast at a time, and as it frequently happens that some of the plates are not as smooth or finely finished as others, in selecting plates for the top cover, the perfectly 45 finished samples can be used, leaving any rougher finished castings for the base plates. Heretofore it has not been usual to provide exactly similar plates for the top and bottom of the reservoir, so that with the older 50 constructions it frequently happens that the top covers have to be discarded on account of the finish, while with my construction there is no such loss as such plates can be used for the base plates.

55 Central openings are drilled in the base

and top cover, and through these openings projects the hollow stem 7. This stem is provided with the flange 8, to form a suitable support for the base plate, and a washer 9, is interposed between the flange and plate 60 to prevent leakage. The base of the stem 7, is provided with a central bore 10, for the passage of the oil, and the lower portion of the stem is screw threaded exteriorly for the reception of the sight feed casing 11, provided with sight openings 12, within which casing is mounted the glass cylinder 13, held between the base of the stem, and a shoulder on the casing with suitable gaskets to prevent leakage. The lower end of the 65 sight feed casing is screw threaded at 14, for securing same on the mechanism to be lubricated. The hollow stem 7, projects upward through both the base and top plate, and is threaded exteriorly above the cover 70 plate for the reception of the locking nut 15, by means of which the base and cover plate and the glass cylinder 1, are held securely 75 together.

16 is the needle valve which is seated in 80 the base of the hollow stem for regulating the flow of the oil, which enters the valve chamber through the openings 17—17, in the hollow stem at the bottom of the reservoir, and thence the oil passes through the 85 passageway 10, whence it drops from the nozzle 18, on the lower end of the stem, past the sight windows 12.

The upper end of the hollow stem 7 is screw threaded interiorly for the reception 90 of the threaded hollow sleeve 19, and 20 is the stem of the needle valve 16, which passes up through the hollow stem 7, and the hollow sleeve 19. A shoulder 21, is formed on the valve rod 20, and a coiled spring 22, is 95 mounted on the rod, bearing between the shoulder 21, and the lower end of the hollow sleeve 19, to hold the needle valve to its seat. The hollow sleeve 19, is provided with an adjusting nut 23, screwed on the upper 100 end of the sleeve, so that the sleeve can be advanced in the hollow stem with relation to the valve rod 20.

Mounted on the upper end of the valve rod 20, which extends beyond the hollow 105 sleeve and adjusting nut, is a hand lever 24, bifurcated below and pivoted to the valve stem by the pin 25. The lower ends of the bifurcated lever bear on the flanged collar 26, mounted loosely on the 110

valve rod, and the pivot point of the lever is so located that when the lever is raised into vertical position, the valve will be raised from its seat, and when the lever 5 is turned into horizontal position, the coiled spring 22, will close the valve. It will be understood from this description that by adjusting the position of the sleeve 19, the lift of the valve rod and valve will be adjusted to determine the amount of oil passing the 10 needle valve. In order to prevent the lever 24, from rattling, I form a second shoulder 27, on the valve stem, and mount a coiled spring 28, between this shoulder and the 15 lower end of the flanged collar 26, so that the flanged collar in all positions of the lever will maintain sufficient pressure thereon to prevent rattling. To prevent vibrations from altering the valve adjustment, a spring 20 arm 29 is secured to the adjusting nut 23, which arm is bent down to engage the knurled surface of the locking nut 15.

The slide cover 6, is mounted loosely on the lower end of the locking nut, to permit 25 the ready opening of the oil reservoir for filling through the opening 5. An air opening 30, is provided for this slide cover and the slide is bent slightly lengthwise so as to be held by the pressure of the locking nut in any position it may be placed, and so that it will not jar open under vibration. The

hollow stem 7, is also provided with an air opening 31, to prevent any back pressure in operating the valve.

Having thus described my invention, what 35 I claim as new and desire to secure by Letters Patent, is:

In a lubricator, the combination of a hollow stem, a valve rod slidable therein, a valve having its seat in the lower end of said hollow stem, a hollow sleeve secured within said hollow stem at the upper end, an adjusting nut to advance said sleeve, said valve rod extending through said hollow sleeve and nut, there being a shoulder on the valve 40 rod, a coiled spring bearing between said shoulder and the lower end of the hollow sleeve, a lever pivoted on the upper end of said valve rod to raise the valve rod against the pressure of said coiled spring, a flanged 45 collar loosely mounted on the upper end of said valve rod and interposed between said adjusting nut and the lever and upon which the lever bears, and a coiled spring bearing 50 between said rod and flanged collar to keep 55 the latter in constant engagement with said lever.

FLOYD L. SWANBERG.
